DESIGN FOR A ROLLER BLOTTER

Lucy Cotton, Miami, Fla.

Application November 7, 1944, Serial No. 116,207

Term of patent 14 years

(Cl. D74—1)

To all whom it may concern:

Be it known that I, Lucy Cotton, a citizen of the United States, residing at Miami, in the county of Dade and State of Florida, have invented a new, original, and ornamental Design for Roller Blotter, of which the following is a specification, reference being had to the accompanying drawing, forming part thereof.

In the drawing:

Fig. 1 is a perspective view of a roller blotter, showing my new design.

Fig. 2 is a side elevational view.

Fig. 3 is an elevational view of one end of the roller blotter.

Fig. 4 is an elevational view of the other end of the blotter.

The essential features of my design for a roller blotter reside in the specific configuration of the handles in combination with the central blotter holding element, all as illustrated.

I claim:

The ornamental design for a roller blotter, as shown and described.

LUCY COTTON.
